S. George Tate
ATTORNEY.

UNITED STATES PATENT OFFICE.

EVA B. NORTON, OF NEW YORK, N. Y.

IRRIGATOR.

Application filed March 6, 1928. Serial No. 259,524.

This invention relates to new and useful improvements in irrigators adapted particularly for use in vaginal and rectal douching.

Among the several objects of my invention are to provide a liquid container which is especially adapted to be supported on a wall and connected to the hot and cold water pipes and to the drain pipe of the ordinary house plumbing system, although from certain aspects my invention may be portable and thereby used wherever desired; to provide such a container with a removable closure having an egress opening adjacent the overflow whereby gases may readily escape to the atmosphere; to provide the inner face of the rear wall of the container with suitable indicia indicative of the volume of liquid within the container; to provide such a container with a valved discharge nozzle to which a douching or other instrument may be readily attached preferably by means of a rubber hose, and to provide such a container which is extremely simple in construction and therefore cheap to manufacture.

With these and other objects in view which will more fully appear, the nature of the invention will be more clearly understood by following the description, the appended claims, and the several views illustrated in the accompanying drawings.

In the accompanying drawings:

Fig. 1 is a perspective view of an irrigator constructed in accordance with my invention.

Fig. 2 is a vertical sectional view showing the application of my invention to a wall and to the plumbing system.

Fig. 3 is a vertical section of the container taken at right angles to Fig. 2, and

Fig. 4 is a bottom plan of the closure.

Like reference numerals designate corresponding parts throughout the several figures of the drawings.

Referring to the drawings, my invention comprises a liquid container A which embodies a bowl 5 of any desired shape, but is preferably provided with a flat rear wall 6 which extends upwardly for a considerable distance above the upper edge 7 of the bowl to form an extension 8 and is provided with openings 9, 10 for receiving the hot and cold water spigots or outlets 11, 12 of the house plumbing system, the flat rear wall 6 permitting the container to be placed in flat contact with the wall 13.

The rear wall 6 is provided with an over-

flow or drain opening 14 which is located slightly below the upper edge 7 of the bowl. I preferably form the overflow or drain opening 14 in the rear wall 6 and direct the opening or passage downwardly to the bottom of the rear wall at which point it is placed in communication with the drain pipe 15 of the house plumbing system. If desirable, a perforated guard plate 16 may be positioned at the inlet of the drain passage.

The front face of the rear wall 6 of the bowl is provided with suitable indicia 17 for indicating the volume of liquid in the container. I preferably employ a plurality of spaced horizontal depressed lines for this purpose, the alternate lines being of different lengths and serving to indicate the volume by quarts and pints.

Fitted to the lower portion of the bowl, preferably at the front thereof, is a valved discharge spigot 18 to which a douching or other instrument (not shown) may be readily attached by a rubber hose 19.

A closure 20 is removably seated on the upper edge 7 of the bowl and is provided with a hand piece 21 for use in positioning the closure on the bowl or removing the same therefrom. The closure is formed on its under face with a peripheral flange 22 which cooperates with the wall of the bowl to retain the closure in position. The rear portion of the closure 20, directly above the drain inlet, is formed with an opening 23 for the egress of gases arising from the liquid within the bowl.

From the above, it will be appreciated that in hospitals much time will be saved in emergency cases by the convenience this irrigator affords in irrigating wounds, rectal injections, douches, etc., and also that the invention may be employed in homes either in connection with the plumbing system or separate therefrom.

It is of course to be understood that the details of structure and arrangements of parts may be variously changed and modified without departing from the spirit and scope of my invention.

I claim:

1. In an irrigating device, the combination of a liquid container having a rear wall and an open top, a closure for said container, said rear wall having an overflow passage formed therein, the closure being formed with an opening located adjacent said overflow pas-

sage for permitting the egress of gas from the liquid, and a discharge outlet near the bottom of the container.

2. In an irrigating device, the combination of a liquid container having a rear wall and an open top, the rear wall having an overflow passage formed therein, a closure for said container, the rear wall extending above the upper edge of the container and provided 10 with a pair of openings for receiving hot and cold water discharge pipes, and a discharge outlet near the bottom of the container.

3. In an irrigating device, the combination of an opaque liquid container having a rear wall and an open top, a closure for said container, the inner face of said rear wall being provided with indicia indicative of the

amount of liquid within the container, said rear wall being provided with an overflow opening adjacent the upper edge of the container, the closure being formed with an opening located adjacent said overflow opening for permitting the egress of gas from the liquid, the rear wall extending above the upper edge of the container and provided with 25 a pair of openings for receiving hot and cold water discharge pipes, a valved discharge spigot connected to the lower part of the container, and a flexible discharge pipe connected to said spigot.

In testimony whereof I hereunto affix my signature.

EVA B. NORTON.
